UNITED STATES PATENT OFFICE

HENRY E. SHEETS, OF SHELBY, OHIO, ASSIGNOR TO THE SHELBY SALESBOOK COMPANY, OF SHELBY, OHIO, A CORPORATION OF OHIO.

MANIFOLDING BOOK.

Application filed September 7, 1922. Serial No. 586,606.

The invention relates to manifolding devices such as manifolding books and with respect to its more specific features to the construction of a transfer sheet and the devices 5 for holding it in operative relation.

One of the objects of the invention is the provision of a manifolding book wherewith two, three or more copies may be made at one writing and wherein the transfer sheet 10 may readily be applied and removed from operative position.

Another object of the invention is the provision of a manifolding book of the character above referred to adapted for manipulation 15 without necessitating the grasping of the transfer leaf in the ordinary operations of setting and manipulating the book.

Other objects will be in part obvious and in part pointed out hereinafter.

20 The invention accordingly consists in the features of construction, combinations of elements and arrangement of parts which will be exemplified in the construction hereinafter set forth, and the scope of the application 25 of which will appear in the appended claim.

In the accompanying drawing forming part of the specification and wherein similar reference characters refer to similar parts throughout the several views,

30 Figure 1 is a perspective view of a manifolding book embodying the invention;

Fig. 2 is plan view, partly broken away; and

Fig. 3 is a perspective view of a section of 35 the backing showing the relation of the transfer sheet.

Referring now more specifically to the drawing, the numerals 1, 2 and 3 indicate three sections of a backing, these sections being hinged together at 4 and 5. The sections 40 are preferably of stiff material and may be covered with cloth, and the cloth may be utilized to provide the hinges 4 and 5. The numeral 6 indicates a pad removably held to one end of the backing section 3 by the spring clip 7. This pad may be composed of a plurality of similar sets of original and duplicate leaves, preferably opaque leaves of soft material, as paper, adapted for 45 transfer of inscription from one to the other through the interposition of transfer material. In Fig. 1 the uppermost set of these leaves is shown with the original leaf 8 thrown back to disclose the duplicate leaf 9.

These two leaves may be formed from an integral sheet reversely folded on itself and weakened along the line 10, the duplicate leaf being extended to provide the usual stub portion for binding it in the pad. In addition to the sets of record leaves as 8 and 9, 55 the pad includes a series of tissue record leaves 11 bound to the pad above the uppermost set of record leaves 8 and 9. The same staples 12 may be used to bind both kinds of record leaves and form the stub end of the 60 pad. In Fig. 1 the tissue leaves 11 are shown as thrown back.

The numeral 13 indicates a transfer sheet or leaf which is adapted to be manipulated into and out of superposed relation with the record leaves of the pad 6. In the embodiment illustrated the transfer leaf 13 is held between relatively movable clamping jaws 14 and 15, these jaws upstanding from the side of the backing section 3, the jaw 14 having a flange 16 riveted or otherwise fastened to the face of said backing section to hold this jaw in place. The transfer leaf 13 may be coated on its opposite faces with carbon transfer material and at its outer free edge 70 is provided with cutaway portions, or access notches which, in the present embodiment, are formed by cutting off the corners of the otherwise rectangular transfer sheet 13 as indicated at 17 and 18.

To set the book for making three copies at one writing the transfer leaf 13 is swung, or moved, around the clamp as an axis into position lying upon the duplicate leaf 9 of the uppermost set of original and duplicate leaves. Thereupon one of the tissue leaves 11 (the uppermost leaf 11 as viewed in Fig. 1) is moved to lie upon the transfer leaf and thereafter the original leaf 8 of the uppermost set is folded on the line 10 to lie upon the interposed tissue leaf. Inscription made upon the upper face of the original leaf will be transferred to the duplicate leaf 9 and to the underface of the triplicate tissue leaf 11 and may be read through the latter. After inscription the original triplicate and duplicate leaves of the inscribed set may be grasped at the lower right hand corner adjacent the access notch 18 in the transfer leaf, but without gripping the transfer leaf, and by a sidewise movement the duplicate leaf 9 may be torn from the stub of the pad along a weakened line adjacent the stub. 90 95 100 105

The original leaf of the next underlying set will then be disclosed underlying the transfer leaf 13, the upper free end or right hand corner of the original leaf presenting itself toward the stub and outside the margin of the adjacent access notch 17. This exposed portion of the original leaf may be grasped, without touching the transfer leaf, and drawn from beneath the transfer leaf, permitting the transfer leaf to rest upon the next duplicate leaf 9. Thereupon the book again may be set for inscription as above explained.

The transfer leaf preferably includes an extended transfer leaf portion 20, conveniently made integral with the transfer leaf 13 and preferably a duplicate thereof and including access notches 21 and 22 like those at 17 and 18. In the embodiment illustrated 20 the integral transfer sheet, composed of the portions 13 and 20, is gripped at an intermediate part between the jaws 14 and 15 so that the immediately operative portion 13, thereof emerges from between these jaws 25 on a line 23, spaced above the face of the backing 3, whereas the transfer leaf portion 20 emerges from between the same jaws in a plane approximating that of the face of the backing 3, and is adapted to lie on said backing and be held smoothly by the overlying pad 6.

Thus it will be seen that when the transfer leaf portion 13 has become worn through use, or when it becomes torn or otherwise marred, the jaws 14 and 15 may be separated and the transfer sheet removed and reversed end for end and the transfer leaf portion 20 utilized for interleaving with the record leaves. The clamping jaws 14 and 15, as illustrated, provide wide surfaces resulting in the effective gripping of the transfer sheet and thus there is practically no tendency for the holding device to impair the held part of this sheet, nor is the sheet weakened as it would be were it stitched or otherwise similarly fastened to the backing 3 or to the pad 6.

In Fig. 2, the record leaves of the uppermost set are shown in position for inscription, a tissue, or triplicate leaf 11, being beneath the original leaf 8, and lying on the transfer sheet 13, which, in turn, lies on the duplicate leaf 9. It will be seen that the upper and lower outer corners of the original and duplicate leaves lie superposed relative to the recess notches 17 and 18, per-

mitting their being grasped at those corners without touching the transfer leaf.

Thus by the above described construction are accomplished among others the objects 60 hereinbefore referred to.

As many changes could be made in the above construction and many apparently widely different embodiments of this invention could be made without departing from 65 the scope thereof, it is intended that all matter contained in the above description or shown in the accompanying drawings shall be interpreted as illustrative and not in a limiting sense.

Having described my invention, what I claim as new and desire to secure by Letters Patent is:

A manifolding book including, in combination, a binding stub, a plurality of record sheets bound together at one edge into said stub so as to swing therefrom, each record sheet being folded backwardly upon itself intermediate its ends to form two relatively superposed record leaves including 80 a bound leaf held within said stub and a reversely disposed leaf carried by the free end of said bound leaf and having its free end disposed toward said stub, a transfer sheet, transfer sheet attaching means for 85 attaching the transfer sheet to the book, said attaching means being relatively positioned with reference to said binding stub so as to support the transfer sheet for swinging movement from the side of the book at an 90 angle to the swinging movement of said record sheets into manifolding relation successively between the said leaves of the successive record sheets, said transfer sheet having cut away portions positioned at parts 95 thereof spaced along its free edge, one of said cut-away portions, when said transfer sheet is in transfer position between the two record leaves of one of said record sheets, being adjacent the fold of said record sheet 100 whereby a portion of the latter is exposed from overlapping relation with said transfer sheet to present a grasping area, and another of said cut-away portions being positioned nearer said binding stub whereby 105 the next successive reversely disposed leaf is exposed toward its free end through the cut-away portion from beneath the overlying transfer sheet.

In testimony whereof I affix my signature.

H. E. SHEETS.
